METHOD AND APPARATUS FOR MAKING
ARTIFICIAL STONE

Carol F. Baron, Brooklyn, N. Y.

Application November 18, 1936, Serial No. 111,411

11 Claims.

(Cl. 25—2)

This invention relates broadly to the art of making molded concrete blocks, such as are commonly used in the erection of buildings, and it deals with the methods, as well as with the apparatus, employed in the manufacture of such blocks.

One object of the invention is: to provide an improved method for manufacturing concrete blocks, which method renders it unnecessary to touch the block from the time the concrete is poured into the block-mold, to the time when the blocks are set and cured, and ready for the builder's use.

Another object of the invention is: to provide a simple and efficient apparatus in/on which the blocks are formed or cast in molds and may there remain during further treatment and until finished, and then be removed individually, one after another, and stored in close and compact formation. Referring to the apparatus specifically, so as to permit the manufacture and removal of the finished blocks along the lines indicated above, the invention provides a plurality of adjacent concrete-receiving molds or receptacles 25 separated from each other by comparatively thin partitions which may be readily primarily assembled to form such receptacles, and which can be readily withdrawn or disassembled to release the finished blocks, for removal.

30 Inasmuch as my improved method of making the blocks, and the apparatus for doing so, are very closely allied with each other, and their relationship as to the position of the blocks on/in the apparatus remains the same throughout the entire process, the following description of the invention will explain the entire process, step by step, commencing with the primary building-up of the apparatus to prepare it for receiving the concrete mixture in the block-molds, and following the successive steps required to produce the finished blocks, without, in the least, changing their positions in/on the apparatus during that period, and finishing with the final taking down 45 of the built-up mold parts to liberate the finished blocks for removal and storage.

Referring to the drawings:

Figure 1 is a perspective view of the apparatus, the uppermost portion being partly broken-away to disclose the molds filled with concrete mixture.

Fig. 2 represents a side view of the apparatus, with the hood raised.

Fig. 3 is a cross section, on line 3—3 of Fig. 2, 55 the hood being down in operative position.

Fig. 4 is a longitudinal section, without the hood.

Fig. 5 is a plan view of the apparatus, with the molds in place, and corresponding to Fig. 4.

Fig. 6 illustrates one step in building-up the 5 molds on the table.

Fig. 7 shows, in perspective view, one end of the frame which forms a part of and supports the hood fabric to form the curing chamber of the apparatus.

Fig. 8 illustrates a modification of the end-closing plate of the molds to be used for forming full-length end-blocks, such as shown in Fig. 9.

Fig. 9 shows a full length end-block.

Fig. 10 shows a half-length end-block.

Fig. 11 is another modification of the end-closing plate, this species being adapted for making jamb-blocks, a full-length block being also shown in this figure.

Fig. 12 represents a half-length jamb-block, also producible with the use of the end-plate shown in Fig. 11. Rows of any of the types of the blocks just described may be cast at the same time with the regular wall blocks.

Fig. 13 represents a number of block-courses, sectionally, as they are built-up in horizontal for floors, or in vertical layers for walls.

Fig. 14 shows, in perspective view, the manner in which staggered or overlapping superposed courses of blocks are laid, each course here having one end-block, one regular block, and one jamb-block to provide for a window or a door casing.

Fig. 15 is a perspective view of a regular block 35 provided with a special facing applicable to the block while in process of manufacture.

In the manufacture of concrete blocks, it has been, and still is, common practice to cast a large number of such blocks at the same time on a table adapted to be transported immediately, after the molds are filled with the desired concrete mixture, from this filling station to another location where the freshly-poured casts are subjected to special treatments, and thus permit another table with a new set of molds to be placed under the chute bringing the fluid concrete from the mixer. Ordinarily, each table is placed on, or forms a part of, a car which must needs be strong enough to carry the weight and yet be easily movable for travel, as for instance on rails which, however, in accordance with my present invention, need not necessarily extend into any building or chamber to bring the molds into locations for further treatment. In other 55

words: the car may now be entirely in the open, because such enclosures, as are required to confine the molds for treatment, may, in one aspect of my present invention, be applied directly to the car itself, in contradistinction to the usual manner of running the car into one or more buildings or chambers built permanently and especially for that purpose.

The car, such as at present preferred, comprises 10 a pair of longitudinally-extending base-channel bars 20 supported by track wheels 21 in any convenient manner. Extending laterally across the channels 20 and supported thereby are a series of smaller channeled beams 22 carrying the table 15 plate 23 on which the block-molds are removably built up into definite positions relative to each other, as follows:

The formation of the molds must, as a matter of course, conform to the type of block to be 20 made, the preferably regular type being shown in Fig. 6. This block B is substantially a rectangular parallelepiped having a centrally cored transverse hollow channel a extending through it and at each end a semi-cylindrical groove b 25 so that, when a series of blocks are placed end-to-end, each pair of adjoining grooves b will also form a cylindrical transverse passage similar to the channel a. Likewise, when a series of blocks are placed flatwise and in overlapping or regularly-staggered courses, the channels a of one 30 course and the end-grooves b of the adjacent course will be in alignment vertically or horizontally, as the case may be, and form passages for ventilation or conduits for wires, pipes, etc. as may be desired when outfitting a building. 35 Of course, it will be understood, that, when erecting a building, the adjoining blocks are to be united by a suitable cement binder.

According to the present invention, the molds 40 for the regular blocks are built-up into composite formation by assembling a number of plates, of which there are used three specific kinds, viz: partition-plates 25 extending across the table, spacer plates 26 placed longitudinally of the table 45 and between the partitions 25 to form rectangular boxes or molds, and end-plates 27 which also extend across the table and are firmly but removably secured to the table-top, (preferably by withdrawable bolts or pins) and which, when so 50 attached, will hold the entire assemblage firmly together, and against shifting on the table.

Considering first the end-plates 27, (see Figs. 1 to 4) they are formed of sheet metal and have 55 their opposite ends attached, preferably by spot-welding, to angular reinforcing or stiffening strips 28, each having at its lower end a perforated ear 28a to receive a lock pin 29 for securing that end of the plate 27 to the vertical leg of an L-shaped guide rail 30, two of such rails being 60 provided and fixed to the table-top near the side margins thereof, respectively, and so distanced from each other that the ears 28a will closely contact the inner faces of the rails 30. Each strip 65 28 has also an upper ear 28b to which is secured the upper end of a brace 31 whose lower end is detachably held against the outer side of the rail 30 by a lock pin 32, both pins 29 and 32 preferably having eye-ends to facilitate their withdrawal, when required. Inasmuch as the 70 end-plates 28 and their attaching devices are duplicates, and the extreme length of the end-plates 28, as well as of the partition-plates 25 is the same throughout, the guide rails 30 are parallel and therefore hold those plate edges in 75 proper alignment longitudinally of the table; it

being understood, of course, that the plates are disposed at right angles across the table and relative to the rails, see Fig. 4.

Considering next the partition-plates 25, these are similar in size and shape to the end-plates, 5 excepting their end strips 28a' which are here bent into U-form and do not have any holding ears. Attention is called to the fact that the spaces between the inner edges of the two opposite strips of each plate must be exactly the 10 same to provide for properly placing the partition-plates so as to leave uniform block spaces between them. Also, that the distance from each inner end-strip edge to the outer face of the strip-bend must be uniform, to insure parallelism 15 of the guide bars with the inner strip-edges to provide for proper location of spacers 26.

The spacers 26 are merely plain thin sheet metal plates (see Fig. 6) all of which are exactly of the same size, so as to be interchangeable ad lib., 20 and which are interposed between the opposite faces of the several partitions and also their cooperative end-plates. As it is important that these spacers 26 must be equally distanced from each, across the table, so that the widths of 25 the molds for the cast blocks will all be the same, means are provided on the partitions and on the working faces of the end-plates, for accomplishing that result, and, in accordance with my present invention I make use of a row of cores C required to produce the grooves b in the ends of the 30 cast blocks B. In Figs. 1 and 4 it will be seen that the table is here adapted to handle six longitudinal rows of blocks, each row consisting of seven blocks, making a total of forty-two blocks 35 for each setting. Therefore, six sets of groove-cores are required on each of the two opposite contact faces of each partition, and, in order to produce the partitions as light in weight as possible, I preferably form all the cores C from thin 40 sheet metal into semi-cylindrical shape provided with top and bottom attaching tabs c which latter may be spot-welded on the working faces of the several plates. The length of each groove-core is equal to the width of the block to be made, 45 and the spaces between each adjacent pair of cores on the plate are equal to the thickness of the spacers which fit snugly between them and abut the working faces of the partitions. In other words: when a pair of cooperative spacers are 50 properly engaging the partitions between which they are located, there will be formed a rectangular mold, whose end walls respectively have the cores necessary to produce the end-grooves, b, b of the block B. Also, inasmuch as the spacer- 55 ends contact firmly against the faces of the partitions, and the spaces which the plate-ends enter between the cores are equal to the thickness of the spacer-plates, it follows that, even if the cores C are, per se, open at both ends, yet there can 60 be no leakage of concrete mixture into the cores because the side face of the spacer-plates seal them.

In Figs. 1 and 4, the partition-and-core combination has been clearly illustrated, attention 65 being now called to the fact that the upper and lower edges of the core-tabs do not extend to the upper and lower faces of the block, so that the full contour of the block-cast may be preserved. On the other hand, the thickness of the 70 tabs will naturally leave a slight depression equal to their thickness in each end-face of the block, and for that reason I preferably feather the tab-edges, to reduce and taper this depression in the manner shown. The same construction applies 75

to the cores C attached to the end-plates 27, only one set however being required for each end-plate. When building-up the molds, one end-plate 27 being fixed in position, the first set of six spacers 5 may be entered into the spaces between the cores C of the end-plates, whereupon the first partition-plate 26 is slid along between the rails 30 until the still free edges of the spacers are entered into the spaces between the cores on the partition 10 and there contact the face of the partition. The same operation is performed with the second set of six spacers being entered between the cores C on the obverse face of the first partition, and the second partition is properly located. It is 15 evident that, if the end-plate 27 is disposed at right angles relative to the guide rails 30, the partition-plates will also be thus disposed, due to the fact, that the spacers are all interchangeable and of exactly the same size. After the last 20 set of spacers has been placed, the final end-plate is brought into engagement with the still free spacer-edges and then locked by the insertion of the lock pins 29 and 32, thus providing, in the exemplary apparatus shown in the 25 drawings, a series of forty-two adjacent and interconnected molds, any pair of which are separated from each other across the table by only one member, viz.; one spacer-plate 26; and longitudinally of the table by a single partition-plate 25, features which are helpful and economical 30 when screeding the concrete mixture in the molds, by a lute or similar device.

Referring again to the block B of Fig. 6, each of the molds assembled as above described, takes 35 care of a rectangular concrete-block as far as its general dimensions and the end-grooves, b, b are concerned. It, therefore, remains only to provide in the molds means for forming in each block the interiorly-central conduit or channel 40 a, so that, when the finished blocks are laid in overlapping courses when erecting a building, the conduit a of one layer or course will line-up with another conduit formed by the combined semi-cylindrical grooves b, b of any pair of adjoining blocks. For that reason, each spacer-plate 26 has a central aperture 26a of a diameter 45 equal to that established by the combination of the grooves b, b of the pairs of adjoining blocks, all the apertures 26a of the spacers therefore becoming aligned and adapted to receive a single core structure, such as 35, shown in Fig. 6 and 50 preferably formed of a cylindrically-curved strip of sheet metal whose outside diameter is substantially equal to that of the apertures 26a, and whose length is sufficient to have its ends project 55 (see Fig. 4) slightly beyond the outer faces of last spacers for each transverse row of blocks on the table. The cores 35 are then pushed through the aligned spacer-apertures 26a, in which they fit 60 closely, and their projecting ends are then expanded, preferably by tapered plugs 36, so as to have a tight fit in the apertures of the outermost spacers of each particular row, and thus seal the 65 molds against leakage. The insertion and end-expansion of the cores 35 constitute the final step in building-up the forty-two molds of the apparatus, and they are now ready to receive such concrete mixture as may be commensurate with the requirements, directly from a mixer (not 70 shown). If required by the nature of the concrete mixture, the table 23 may be equipped with a vibrator V (see Fig. 1) to agitate the mixture as it settles in the molds, and to thereby densify the cast, even before the curing operation is 75 begun.

In recapitulation be it stated that the above-described manner of building-up the molds from pluralities of partition-plates 25, spacers 26 and end-plates 27 respectively, is a simple process which, although possibly requiring slightly more 5 time in its accomplishment, when compared with the time required for assembling a set of individually-separable molds, possesses the advantage that the entire mold outfit is light in weight, costs less in producing the necessarily large number of parts, eliminates waste of mixture due to screeding the casts when the molds are filled, and also permits rapid removal of the finished blocks, without any liability of damaging the 10 finished block faces or corners by having them 15 stick to the sides of preformed box-type molds as used heretofore.

When all the molds are filled from the mixer, the car may be rolled out from under the mixer or filling station to another nearby location 20 where the casts are to be dehydrated and cured, a process which was heretofore generally carried out in an enclosed building or room where the casts were kept for a sufficient period, usually from one week to ten days, to permit the 25 mixture to set or harden to a small extent before any actual heat was applied, during which setting period the casts were protected from the direct rays of the sun and from drying winds, by 30 covers of canvas, burlap, or sand.

In my improved method, I do not employ any 35 coverings of any kind during the setting period, but allow the casts to harden or set naturally for a period of about one to two hours, according to atmospheric conditions, a short period if temperature is warm, and a longer period if the temperature is cold. The central cores 35 are then 40 released by the removal of the plugs 36, and withdrawn, leaving the central channels a open and unobstructed from end-to-end, and ready 45 for steam-curing, which latter is accomplished under a hood normally suspended in raised position and adapted to be lowered to entirely enclose the table top and the filled molds supported thereon.

In conformity with my present invention, this 50 hood and the steam-supplying elements are combined into a single unit comprising a series of bows H¹ which are centrally spaced at the top on a tie-plate H², and whose opposite side ends H^{1a} 55 are substantially vertically parallel and are attached to nozzles N projecting toward each other from a pair of steam-supply pipes 37, 38 which extend in parallelism with, and are supported along, the sides of the mold-carrying table 23, 55 respectively. The nozzles N of each pipe are so spaced longitudinally thereof that, when the pipes are placed into their positions on the table, their respective nozzles will be in alignment with and facing the outer openings of the central 60 channels a. At one or both ends of the car, the steam pipes 37 and 38 are rigidly connected preferably by pipes and fittings such as shown in Fig. 7, each of the connector branch pipes 37a, 38a being provided with a valve 39, whereby the 65 passage of superheated steam at about 250° F., supplied through a flexible steam-house 40, may be regulated, as weather and temperature conditions may dictate to produce the best results. From the foregoing it will be understood that the 70 steam pipes and their associated bows and nozzles form a strong unitary frame which may be covered with canvas H over the top and ends, and whose side aprons h hang over and are 75 adapted to entirely enclose the sides of the molds.

on the table, and thus form a closed hood adapted to be raised or lowered over the molds by a suitable tackle or crane (not shown) attachable to the hood at eye bolts, as shown. Inasmuch as it is necessary that the hood be properly located on the table so as to bring all the nozzles *N* into alignment with the cores *a* of the blocks, respectively, there are secured to the table top *23* a series of brackets or stands *41* whose upper ends are bifurcated, as at *41a*, to receive and support the side steam pipes *37*, *38* at their required altitude above the table-top, and also to act as side gages or stops to be contacted by the T-fittings such as *37b*, *38b* of the pipes *37*, *38* respectively, to locate the nozzles properly lengthwise of the table.

As shown, the top of the hood is crowned and located closely over the tops of the molds, a feature which maintains the emanating gases warmer and closer to the product and also tends toward economy by the conservation of steam, the condensation of which will naturally accumulate on the underside of the canvas-covering and run off toward the side aprons of the hood and to the table-top where it will undergo more or less of revaporization, according to the temperature of the table as produced by live steam issuing from the nozzles into the hood, and particularly into the open ends of the cored channels *a* of each transverse row of block-casts. The steam-jets are therefore projected toward each other, bringing their initial heat into direct contact with the bare interiors or channels of the hollowed block-casts and thereby hastening the curing of the latter in a very substantial manner, from the inside of the cast toward the outside thereof. Furthermore, inasmuch as the several spacer-plates are made of metal, they will also become hot, by virtue of the live steam coming into direct contact with the edges of the plate perforations *26a*, and thus assist in dehydrating the casts, especially at the side faces thereof, during the curing operation, the latter taking only from four to eight hours, depending upon the particular concrete-mixture and the latent heat of the vapor.

At the expiration of that period, the steam-valves are closed, and the hood is raised. The steam-cured casts and the molds are then to be exposed for gradually cooling-off and consequent contraction and resultant densification or hardening, this process requiring from one to two days, depending upon the atmospheric conditions. Upon the conclusion of this curing period the molds and blocks are taken apart, piece by piece, and stacked, the blocks being then completely finished and ready for immediate use.

When taking-down or disassembling the molds, one or both of end-plates *27* are liberated by the withdrawal of the securing-pins *29*, *32* and removed from the table. The outer ends of the first row of spacer-plates *26* will therefore be freed and may be pulled out to clear the sides of the blocks, without any liability of breaking or otherwise damaging either the corners or faces of the blocks, the blocks being thereupon removed from the table as fast as the spacer-plates *26* are taken out, that is to say: very speedily, as compared with the time required to slide finished cast blocks out of either unitary or individually-assembled molds, with their accompanying danger of damaging the cast blocks and thus causing waste of product.

The blocks which are to be cast on my improved apparatus can, of course, be any of the

various types used in the erecting of buildings, all the blocks matching cross-sectionally but differing at their ends to meet different purposes, as illustrated in Fig. 14. In Fig. 9 there is shown a full-length terminal or end-block *E* such as 5 may be used for floors or partitions at their junctions with walls, etc., in which case the semi-cylindrical groove *b* is dispensed with at one end, the block then having a full face end *b'*. The end-plate *27* against which those blocks are cast, 10 should therefore not have any cores *C*; so that other means have to be provided for properly spacing the end-edges of the last row of spacer-plates where they abut against the inner face of the end-plate. In the preferred form thereof 15 shown, these means consist in forming the spacers *45* so as to have tabs *45a* (see Fig. 8) projecting beyond the edge of the plates and adapted to enter slots *46* provided for them in the end-plate *47* at proper distances between them. In Fig. 10 20 there is shown a half-length end-block *Ea*, having a plain end-face *b'*, without any end-groove, just like the full-length block *E* of Fig. 9. By referring to Fig. 14 the utility of the half-length blocks *Ea* will be apparent, the lower layer or 25 course *L¹* consisting of a full-length end-block *E*, a regular block *B*, and a half-length jamb-block *Ja*, the latter being shown, per se, in Fig. 12, and having its end notched out at *j* to receive the jamb or casing of a door or window. The next 30 and superposed layer or course *L²* consists here of a half-length end-block *Ea*, a regular block *B*, and a full-length jamb-block *J*, so that the vertical joints between the adjacent blocks of one course will be in staggered relation to the joint 35 lines between the adjacent blocks of the next course. The next superposed layer or course *L³* will, of course, be like the course *L¹*, the courses alternating as they are successively built-up, as is common practice. 40

From the foregoing description the necessity of providing half-length jamb-blocks *Ja*, will be evident, because the casing-receiving notches *j* of the superposed courses must be in vertical alignment, and match. By referring to Fig. 11 45 it will be noted that the notches *j* are formed in the blocks, *J*, *Ja* by substituting, on the inner face of the end-plate *27*, cores *Ca* of rectangular form, for the semi-cylindrical cores *C* used in the casting of the regular blocks *B*, it being understood that the cores *Ca* are spaced to closely receive the edges of the several spacer-plates *26* of that row. 50

It is obvious that, while my invention has been fully explained by the drawings and the description pertaining thereto, the showings are only of exemplary nature, especially in regard to the shapes and sizes of the blocks and the cores necessary to produce them; furthermore that copings, caps, sills and other building-elements can 55 be economically manufactured by my improved method, with equal facility.

As to carrying out my improved method of manufacturing the blocks by the use of the apparatus described, a brief and concise résumé 60 of the successive steps and the pertinent manipulation of the apparatus to carry out those steps, may be in order to clarify the entire situation, from the time of building-up the molds to the time where the finished blocks are removed, ready 65 for use, as follows:

1. Build-up the molds, by assembling the end-plates *27*, partitions *25* and spacers *26*, and securing the end-plates *27* to the table rails *30* by using the pins *29*, *32*. 70 75

2. Place the long center-cores 35 into their positions by passing them through the apertures 26 of the spacers and so as to slightly project beyond the faces of the outermost spacers of each row, and drive-in the plugs 36, to make tight joints and prevent leakage of the fluid-mixture of concrete toward the outside of the outermost molds.

3. Fill the molds, from the mixer chute, and screed their tops.

4. Clear the car from the mixer chute and bring it under the raised hood, (which constitutes the curing station) to protect the molds from direct sun or rain.

5. Let the concrete "set", while in the open, for a period of one to two hours, viz: a short period, if the atmosphere is warm, a longer period, if cold.

6. Remove the core plugs 36, and pull out the center-cores 35.

7. Drop the hood, to completely enclose the molds.

8. Open both steam-valves, to steam-cure the casts in the molds from four to eight hours, by injecting the steam into the central core-channels of the casts, bringing hot vapor into direct contact with the now bare inside of the cast, and curing the latter from the inside, outwardly.

9. Shut-off the steam and raise the hood, letting the molds stand as they are, for one to two days.

10. Take off the end-plates, upon withdrawal of the pins 29, 32.

11. Take the mold-plates and cast blocks apart, piece by piece, and store them away for immediate or future use.

Considering the method involved, the total time actually used from the time that the molds have been filled and screeded, need not exceed three days, maximum which is a considerable saving over the period of from ten days to two weeks required heretofore.

Concerning the apparatus used, the molds can be quickly assembled and locked to and on the table in predetermined positions, without bolts, screws, clamps, or tools. The hood is individual to any car, and can be quickly placed into correct position to line-up all the steam-nozzles with the core-channels of the casts, without requiring adjustments of any kind, either horizontally or vertically. The steam-supply can be handily regulated in accordance with the prevailing condition of the atmosphere, and can be readily disconnected when not needed, either from the hood itself, or by raising the hood from the table. When dismantling the table, the mold-parts of each of the three types used (being exactly alike in shape and light in weight) can be easily stacked or stored in compact form.

60 It is sometimes desirable to make blocks which are coated at their upper faces with a layer of hard veneer, to produce certain color effects, and also a hard wearing surface, especially when the blocks are to be used for flooring. Such a block is illustrated in Fig. 15, where the block B has a top-facing F which may consist primarily of a plastic compound adapted to be spread over the exposed tops of the uncured concrete in the molds, the concrete in that instance being screeded with a lute of variable depth to leave room for the veneering compound which then is screeded level with the tops of the molds and is cured at the same time with the concrete cast. In another instance ornamented or enameled tiles 75 may be applied to the tops of the cured concrete

casts, a cement being then used for intimately binding the concrete block and its veneer together, all while the casts are still in the molds.

It is obvious, of course, that variations and modifications may be made within the scope of this invention and portions of the improvements may be used without others.

I claim:

1. A method of casting interiorly-channelled concrete blocks which comprises projecting jets of steam simultaneously into the opposite open ends of the bare interior channel of each block and against the exterior of the same to cure the block from the inside as well as the outside, and maintaining the warm steam in close proximity to and in contact with the surfaces thereof to maintain the product and gases emanating therefrom at a uniform heat. 10

2. A method of casting and curing concrete blocks in a molding device comprising a plurality of molds having removable cores, the steps of pouring the concrete to fill the molds and screeding the same, initially setting the blocks, removing the core from the molds, enclosing the molds with a means disposed in close proximity to the outer surface thereof, and simultaneously projecting low pressure steam into the channels formed in the concrete blocks by the removal of the cores and to the outer surface of the blocks so as to cure the blocks from the inside as well as from the outside, the steam being maintained in intimate engagement with the product by the enclosing means whereby the product and gases emanating therefrom are maintained at a uniform heat. 20

3. In a method of casting and curing concrete blocks in a molding device having removable cores therein and a curing hood thereon, the steps of pouring the concrete to fill the molds and screeding the same, producing an initial 30 set in the blocks, removing the cores from the mold, lowering the hood into position over the mold in close proximity to the product, and forcing low pressure steam through the channels formed in the blocks by the removal of the cores and also to the outer surface of the same to simultaneously cure the blocks from the inside as well as from the outside, the steam being maintained in close proximity with the product causing a uniform heat to be maintained on the 40 product. 45

4. An apparatus for casting concrete blocks, comprising a table, a series of adjacent molds arranged in longitudinal as well as in transverse rows and secured thereon, a hood movable 50 to expose and completely enclose the table-top and said molds, and steam-supply pipes supporting said hood and having nozzles extending into the interior thereof. 55

5. An apparatus for casting concrete blocks, comprising a table, a series of adjacent molds arranged in longitudinal as well as in transverse rows and secured thereon, a hood movable to expose and completely enclose the table-top and said molds, steam-supply pipes supporting 60 said hood and having nozzles extending into the interior thereof, and devices secured to the table-top for positioning said steam pipes on the table to bring said steam-nozzles into predetermined positions relative to said molds, and simultaneously position said hood over said molds. 65

6. An apparatus for casting concrete blocks, comprising a table, a series of adjacent molds arranged in longitudinal as well as in transverse rows and secured thereon, a hood vertically mov- 70

75

able to expose and completely enclose the table-top and said molds, and steam-supply pipes supporting said hood at the outer sides thereof and having nozzles extending through the sides of 5 said hood into the interior thereof.

7. An apparatus for casting centrally-channeled concrete blocks, comprising a table, a series of adjacent molds arranged in longitudinal as well as in transverse rows and secured thereon, 10 a hood movable to expose and completely enclose the table-top and said molds and steam-supply pipes supporting said hood and having nozzles extending into the interior thereof and adapted to project steam-jets into said channels formed 15 in the blocks in the molds, respectively, at the opposite open ends thereof.

8. An apparatus for casting centrally-channeled blocks comprising a table; a series of adjacent molds arranged in longitudinal as well as 20 transverse rows and secured thereon; a hood movable to expose and completely enclose the table and said molds; and a steam supply pipe supported on said hood and having nozzles extending into the interior thereof and adapted 25 to simultaneously project steam jets into the open ends of said channels formed in the blocks in the mold and to the free exterior surfaces of said blocks to thereby cure the concrete from the inside as well as from the outside.

30 9. An apparatus for casting centrally-channeled blocks comprising a table; a series of adjacent molds arranged in longitudinal as well as transverse rows and secured thereon; a hood

movable to expose and completely enclose the table and said molds; and a steam supply pipe having nozzles extending into the interior of the hood to simultaneously project steam jets into the open ends of said channels formed in the blocks in the mold and to the free exterior surfaces of said blocks to thereby cure the concrete from the inside as well as from the outside. 5

10. A method of casting and curing concrete blocks in a molding device comprising a plurality of molds having removable cores, the steps of molding the blocks and initially setting the same; baring the interior of the block by removing the cores from the molded blocks; and projecting low pressure steam into the interior of 15 the blocks and into engagement with the outer surface thereof to cure the blocks while they are still in the molds.

11. A method of casting and curing concrete blocks in a molding device comprising a plurality of molds having removable cores, the steps of molding the blocks; forming channels extending through the molded blocks by removing the cores; simultaneously projecting low pressure steam into the open ends of each channel and 20 into engagement with the bare interior of the blocks; and maintaining the steam in intimate engagement with the outer surface of the blocks to cause a uniform heat to be maintained thereon and the product cured simultaneously from the 25 inside and outside while in the molds.

CAROL F. BARON.
